Patented Sept. 2, 1913.

UNITED STATES PATENT OFFICE.

LUDWIG OTT, OF KEMPTEN, GERMANY, ASSIGNOR TO HERMANN OTT, LUDWIG OTT, AND ADOLF STEIS, COPARTNERS CONSTITUTING THE PARTNERSHIP OF A. OTT, OF KEMPTEN, BAVARIA, GERMANY.

INTEGRATOR.

1,072,153.

Specification of Letters Patent.

Patented Sept. 2, 1913.

Application filed October 12, 1911. Serial No. 654,397.

To all whom it may concern:

Be it known that I, LUDWIG OTT, a subject of the German Emperor, residing at Kempten, Bavaria, Germany, have invented 5 a new and Improved Integrator, of which the following is a specification.

My invention relates to integrators, often called planimeters, and has for its object to provide an integrator for mechanical integration based upon the same principle as the well known Amsler's polarplanimeter and adapted on the one hand to the determination of plane areas, *i. e.*, to the evaluation of integrals of the type

$$\int_{x_1}^{x_2} y dx$$

using Cartesian coördinates, or of the type

$$\int_{\varphi_1}^{\varphi_2} \frac{\rho^2}{2} d\varphi$$

using Polar coördinates; or, on the other hand, adapted to the solution of classes of mathematical problems which depend upon 25 the evaluation of integrals of the form of

$$\int_{x_1}^{x_2} \frac{x}{\sqrt{x^2 + y^2}} \left(\frac{dy}{dx} - \frac{y}{x} \right) dx, \text{ i. e. } \int_{\varphi_1}^{\varphi_2} \rho d\varphi.$$

30 The character of my invention will be better understood by reference to the accompanying drawings, which are hereby made a part of this specification, in which—

Figure 1 is a plan view of a preferred 35 form of my invention; Fig. 2 is a sectional elevation along the line 2—2 of Fig. 1; Fig. 3 is an end elevation taken from the left (Figs. 1 and 2); and Fig. 4 is a diagram illustrating the theory of my invention.

40 Referring to the drawings my invention consists, essentially, of a main follower A and two directors or guides viz., a director arm B and a polar director C. To use the instrument the follower is employed with 45 either one or the other of these two directors according to the character of the integration as aforesaid and as will hereafter be described in detail.

The follower A comprises a bar *a a'* hav-

ing a rectangular slideway *g g'* cut into its 50 under side for nearly its entire length and provided at one end with a stylus *c* perpendicular to the working plane and adapted to follow the bounding curve of the area to be integrated or the curve to be evaluated. 55 The other end of the follower A is provided with a blunt supporting point or knob *e* projecting from below, and a conical hole *f* comprising coupling means is sunk into the upper side of the follower. Fixed laterally to the bar *a, a'* adjacent to the stylus *c* is an L-shaped yoke in which is mounted an integrating roller *d*. This roller must be accurately adjusted so that its axis *h h'* is exactly parallel to the axis of the follower 60 while its plane of rotation is perpendicular to the working surface and preferably (but not necessarily) passes through the stylus *c*. The axis *h h'* may be at any convenient distance from the axis of the follower A. 65 Rotation of the roller *d* is read upon the graduated drum *k* fixed to one side thereof with the aid of a vernier *l*. The follower thus has three points of support upon the working plane, viz., the stylus, the integrating roller, and the supporting point *e*, and is always in stable equilibrium independently of either the director arm or the polar 70 director.

The director arm B has at one end a 80 downwardly projecting spindle *m* which terminates in a ball adapted to be seated in the conical hole *f*; the other end of arm B engages revolvably with a second vertical spindle provided with a weight *o* and a pin 85 point *n* for holding the spindle in any desired location upon the working surface. When the director arm is coupled to the follower as just described the free end of the follower (the end opposite the one provided with the stylus and the integrating roller) may obviously be swung in a circle the radius of which may be of any convenient length. When this radius is infinity the circle becomes a straight line. 90 Any device for compelling the free end of the follower to travel in a determined circle 95 may be considered as an equivalent of the

director arm specifically described and shown in the drawing.

The polar director C comprises a vertically arranged pin of diameter to just fit within the slideway $g\ g'$. This pin I fix upon a suitable button provided with needle points for attaching it to the working surface.

In the use of my invention I proceed as follows: For the ordinary determinations of plane areas, the follower A is coupled with the director arm B, and the instrument used exactly as is the well-known polarplanimeter from which it does not differ in function but only in appearance, that is to say, the stylus c is made to follow the bounding curve and the integrating roller is read and its value used in connection with the constants of the instrument. If, on the other hand, integrals of the form

20

$$\int_{\varphi_1}^{\varphi_2} \rho d\varphi$$

are to be evaluated in connection with a given curve then the polar director C is to be engaged with the slideway $g\ g'$ of the follower and the director arm B is to be removed. The instrument is then to be used like the conventional polarplanimeter, that is to say, the stylus is caused to follow the curve to be evaluated and the integrating roller read as before.

The theory of my invention may be explained as follows, referring to the diagram Fig. 4:—Let O represent the pole about and through which the follower may be moved, SS' be the curve traced by the stylus, P be the starting position of the stylus, P' be the corresponding starting position for the integrating roller, Q be the position of the stylus after a differential of the curve has been traced, Q' be the position of the integrating roller when the stylus is at Q, OP be a radiusvector or ρ . Then the angle $P O Q = d\varphi$. Then in passing from P' to Q' , the axis h , h' of the integrating roller will include an angle $P' O' Q'$, or $d\varphi$ and the line $P' O'$ will be equal to the radiusvector ρ .

50 In the above described movement, the stylus c will move over an infinitesimally short right line $P Q$ and the integrating roller over a corresponding right line $P' Q'$. This movement of the integrating roller can be resolved into two rectangular components, namely, a rotational movement $P' R'$ of the roller about the pole O' upon a radius ρ and a sliding movement $R' Q'$ of the roller in its own axis. Since there is no rotation of the integrating roller for this sliding movement, the total rotation of the roller will be that corresponding to the line $P' R'$, that is to say, to $\rho d\varphi$. If now, the stylus is made to follow a curve of finite length, the integrat-

ing roller will automatically register the summation of the elements $\rho d\varphi$, that is to say, will evaluate the integral

$$\int_{\varphi_1}^{\varphi_2} \rho d\varphi$$

70

aforesaid.

Having described my invention, I claim:

1. In an integrator for the determination of plane areas, the combination of a follower comprising a bar provided at one end with a stylus, and an integrating roller fixed laterally of but axially parallel with said bar, and at the other end with both a supporting point and coupling means, and means adapted to be engaged with said coupling means for limiting to a circular path the movement of the bar end provided with said coupling means, the bar of the follower being further provided with means for engaging slidably a fixed polar director.

75

2. In an integrator for the determination of plane areas, the combination of a follower comprising a bar provided at one end with a stylus, and an integrating roller fixed laterally of but axially parallel with said bar and at the other end with both a supporting point and coupling means, and means adapted to be engaged with said coupling means for limiting to a circular path the movement 80 of the bar end provided with said coupling means, the bar of the follower being further provided with a longitudinal groove for engaging a fixed pin.

85

3. In an integrator for the determination of plane areas, the combination of a follower comprising a bar provided at one end with a stylus, and an integrating roller fixed laterally of but axially parallel with said bar, and a director arm, the other end of the follower bar having a supporting point and further having detachable pivotal engagement with one end of the director arm, while the other end of the director arm is provided with means for revolvably fixing it in a working surface, the bar of the follower being further provided with a longitudinal groove for engaging a fixed pin.

90

4. In an integrator for the determination of plane areas, the combination of a follower comprising a bar provided at one end with a stylus and an integrating roller fixed laterally of but axially parallel with said bar, and a director arm, the other end of the follower bar having a supporting point and further having detachable universal engagement with one end of the director arm, while the other end of the director arm is provided with means for revolvably fixing it in a working surface, the bar of the follower being further provided with means for engaging slidably a fixed polar director.

95

5. In an integrator for the determination

100

105

110

115

120

125

of plane areas, a follower comprising a bar having a stylus at one end, a supporting point at the other end, and an integrating roller fixed to said bar laterally thereof but 5 axially parallel therewith, the follower being adapted to rest upon stylus, supporting point and roller, said follower being provided at the end distant from the stylus with a universal bearing point and having

further longitudinally arranged means for 10 slidably engaging fixed guiding means.

In testimony whereof I have hereunto set my hand in the presence of two subscribing witnesses.

LUDWIG OTT.
